FOUNDRY APPARATUS

Ralph P. Davis, Squantum, Mass., assignor, by mesne assignments, to Link-Belt Company, Chicago, Ill., a corporation of Illinois

Application June 26, 1951, Serial No. 233,640

13 Claims. (Cl. 22—64)

This invention relates to foundry apparatus and more particularly to metal casting machines for use with shell-type molds.

Molds of the thin walled shell-type are comprised of a major portion of an inorganic molding material such as sand and a minor portion of a component serving to bind the inorganic material. The completed molds are in two or more matching parts having the form of hard thin shells of substantial strength. The inner faces of the matching parts are smooth and finished whereas the outer surfaces are left in a rough and irregular condition. Consequently, during the casting operation using such molds the common weighing methods for ordinary sand molds cannot be used with any degree of success.

The casting machine of the present invention embodies a plurality of casting boxes each adapted to contain a complete mold or molds. As each box reaches a loading position it is filled around the molds with granular refractory material, such as steel shot. Fluid pressure is then applied to flexible liners in the boxes to hold the molds in suitable pouring position while compressing the mold halves together sufficiently to withstand the static pressure of the casting material. Thereafter, the boxes are moved by the machine to pouring position and then to an unloading station for removal of the refractory material. Upon removal of the mold and casting from the casting box it is returned to the initial loading station for another cycle.

The component parts of the casting machine may be summarized as follows:

a. A pair of independently mounted carriers positioned horizontally side-by-side and each carrying a plurality of casting boxes arranged as the rim of a wheel for rotation about the mounting.

b. An overhead hopper mounted between the wheel rims and containing the refractory loading material.

c. A pair of telescopic feed nozzles operatively associated with the hopper for loading one casting box on each carrier simultaneously.

d. Mechanism for opening and closing the hopper outlet and operating the telescopic nozzles.

e. Means for compressing the mold halves together and holding the molds in pouring position.

f. Mechanism for indexing the carriers and casting boxes from the loading stations to the pouring stations to the unloading station.

g. Mechanism for unloading the casting boxes of refractory material and returning this material to the hopper by way of a dust separator and exhaust system.

h. Means for returning the carriers and empty casting boxes to the loading station.

The apparatus so summarized has for an object the expeditious production of all manner of castings from shell-type molds. One or two operators can keep the machine in constant production with a minimum of effort in placing the molds and removing the finished castings after pouring. Relatively unskilled labor may be employed in the production of good quality castings since the opera-

tions involved lend themselves readily to minimum skill. The machine itself is of relatively simple nature embodying uncomplicated parts which are durable and rugged as required in general foundry practice.

Other objects and advantages will become apparent from the following description taken in connection with the accompanying drawings, wherein:

Fig. 1 is a front elevation partly in section of the casting machine,

Fig. 2 is a top plan view of the machine shown in Fig. 1,

Fig. 3 is a side elevation partly in section of the machine,

Fig. 4 is a front elevation on an enlarged scale of a part of the machine,

Fig. 5 is a section taken on the line V—V of Fig. 4,

Fig. 6 is a schematic view of the fluid mechanism, and

Fig. 7 is a detail view of the pressure chamber 144.

Fig. 8 is a wiring diagram of the electrical connections for the control mechanism.

The carriers

Referring more particularly to the drawings, a pair of independently mounted carriers 10 are positioned horizontally side-by-side adjacent the floor line 12 of the foundry. Since each of the carriers is identical with the other, the description of one will suffice for both. Thus, a tubular support 14 extends upwardly above the floor line 12 from a suitable foundation 16 and carries a hollow hub member 18 rotatably mounted on suitable bearings 20. A plurality, in this instance seven, radial arms 22 are secured at their inner ends to the hub portion 18. Underlying the arms 22 and secured thereto by welding or the like is a substantially circular flange 24 carrying a plurality, in this instance seven, driving elements in the form of studs 26 which project toward the floor line 12 but terminate short thereof. The studs 26 are equally spaced around the flange 24 and are respectively positioned intermediate each pair of radial arms 22.

The driving elements formed by the studs 26 are adapted to be selectively engaged by driving means designated generally by the reference numeral 28 (Fig. 2) suitably mounted on a base plate 30 secured to the foundation 16 at the floor line 12. The driving means 28 is preferably power operated and serves to impart rotation to the carrier 10 as desired. To this end, a fluid motor 32 is mounted on a pivot 34 carried by the base plate 30. A reciprocable plunger 36 is operatively associated with the motor 32 for movement substantially perpendicular to the radial arms 22 and carries on its outer end a notched portion 38 suitably formed for operative engagement with an adjacent one of the studs 26. When so engaged, the reciprocable movement of the plunger 36 will serve to impart rotation to the carrier 10 as will be apparent. As viewed in Fig. 2, the right-hand carrier 10 rotates clockwise while the left-hand carrier 10 rotates counterclockwise. Biasing means in the form of a tension spring 40 is operative between the fluid motor 32 and the base plate 30 for maintaining the notched portion 38 in engagement with the adjacent stud 26.

When the reciprocable plunger 36 has completed approximately three-quarters of its travel, a cam 52 acts on a fluid control valve 48 to reduce fluid flow from the fluid motor 32 and thereby reduce the lineal speed of the plunger 36 and the rotative speed of the carrier 10. The cam 52 may have a progressive action on the fluid control valve 48 and thereby cause the rotative speed of the carrier 10 to progressively approach zero as the plunger 36 reaches the limit of its travel.

When the reciprocable plunger 36 has reached the limit of its travel for indexing the carrier 10 one position, it is necessary that it be released from driving engagement

in order that it may return to its initial position while the carrier 10 remains stationary. To this end, a fluid motor 42 is mounted on the base plate 30 and has its reciprocable plunger 44 operable on the motor 32 in opposition to the bias of the spring 40. A swivel connection 46 is provided for attaching the plunger 44 to the motor 32.

The fluid motor 42 is rendered operative for overcoming the bias of the spring 40 by fluid connections to be described hereinafter. The forward movement of the plunger 36 is controlled by the fluid control valve 48 mounted on a bracket 50 carried by the motor 32. The fluid control valve 48 is normally biased open and is operable to closed position by the cam element 52 forming means responsive to movement of the motor plunger 36 to its extended position for operating the valve device 48. The cam element 52 is mounted on a guide rod 54 carried by the notched member 38 substantially parallel with the plunger 36. A slotted guide member 56 carried by the motor 32 is adapted for reception of the cam element 52 to support the same in operative position relative to the valve device 48.

Casting boxes

A plurality, in this instance seven, casting boxes 58 are mounted on each of the carriers 10 for rotation therewith. As the casting boxes 58 are identical in construction, the description of one will suffice for all. Each box 58 comprises a generally rectangular casing of cup-shaped form having a pair of bottom walls 60 spaced one from the other throughout their length to provide a generally rectangular outlet 61 opposite the open end of the box 58. A swivel plate 62 is movable across the outlet 61 between open and closed positions. A catch member 64 projects from the swivel plate 62 for operating this member between positions. A fluid motor 66 is mounted on the base plate 30 to engage and operate the catch plate 64 at an appropriate location, such as the unloading station of this machine. The fluid connections for the motor 66 will be described hereinafter.

The casting boxes 58 are mounted in end-to-end relation on the arms 22 of the carrier 10 to form the rim of a wheel. The boxes 58 may be secured together in such relation and to the arms 22 by welding plate 68 interposed between these members. The box 58 is of sufficient width and length to receive the two halves of a complete mold which is inserted freely in an edgewise direction through the open end of the box 58. It should be observed that the width of the box 58 is sufficient to provide a space between the side walls thereof and the mold which is inserted therein for a purpose apparent hereinafter. The mold is supported on a plurality, in this instance four, support bars 70 which extend transversely across the casting box 58 adjacent the bottom walls 60.

The opposite side walls of the casting box 58 are provided with a pair of liners 72 respectively of generally rectangular form which are secured at their outer edges to the side walls in air tight engagement. The liners 72 are preferably made of flexible sheet material, such as rubber, although any other resilient or elastic material may be employed. Means for admitting fluid under pressure between the side walls of the boxes 58 and the liners 72 are provided and take the form of fluid connections 74 mounted on the side walls of the boxes 58 and communicating with the spaces as formed. These fluid connections 74 will be described in detail hereinafter.

In connection with the disclosure of the casting boxes 58 and connections 74, reference may be had to my co-pending application Serial No. 183,363, filed September 6, 1950, now Patent 2,660,770, issued December 1, 1953, wherein these devices are fully disclosed and claimed.

Hopper

Positioned between the carriers 10 is a pair of supports 76 each of which may be secured at one end in the foundation 16 and having the opposite end projecting there-

from above the floor line 12. The supports 76 carry an overhead container or hopper 78 therebetween for granular refractory material, such as steel shot. The hopper 78 is generally cylindrical in form, but is provided at one end with oppositely disposed rectangular portions 80 which overlie an adjacent pair of the casting boxes 58 respectively on the carriers 10. Such overlying relationship is established at an appropriate location of the carriers 10 and may be termed the loading station of this machine.

Since the rectangular portions 80 of the hopper 78 are identical in form description of one will suffice for both. Referring more particularly to Figs. 4 and 5, the rectangular portion 80 terminates in discharge means for the refractory material which takes the form of a W-shaped portion in cross-section. The adjacent lower apices of the W-shaped form are each suitably slotted to provide two pairs of rectangular discharge orifices 82 which are spaced one from the other in substantially the same horizontal plane. The spacing of the orifices 82 is such that material flowing therefrom will enter the single casting box 58 positioned therebeneath and on either side of a mold therein on each of the carriers 10.

A closure means in the form of a swinging gate member 84 is provided for each of the orifices 82 which are positioned in two pairs as stated. Each gate member 84 is provided with a pair of side plates 85 which are pivoted on the projecting ends of a rod 87 extending across the rectangular portion 80 and are movable in unison to open and close the orifices 82 at appropriate times. Such operation of each gate member 84 is effected by a toggle bar 86 having its opposite ends pivotally mounted on the side plates 85 at one end of the gate members 84 and operable by a plunger 88 of a fluid motor 90. There are two such motors 90 and connections for operating the two pairs of gates 84 although only one is shown in Fig. 4 for the purpose of clarity in illustration. Each motor 90 is supported on a bracket 92 carried by the rectangular portions 78 and having suitable guide means 94 for the plunger 88. As shown in broken lines on Fig. 4, reciprocable movement of the plunger 88 will serve to operate the toggle 86 and move the gate members 84 between open and closed positions. The fluid connections for operating the fluid motors 90 will be described hereinafter.

Feeding means are employed for filling the casting boxes 58 to a predetermined depth with refractory material from the orifices 82. The feeding means take the form of a pair of outlet members 96 having a funnel-shaped end extending across the orifices 82 and terminating in relatively narrow nozzle portions 98 adapted normally to overlie a single casting box 58 on either side of the mold positioned therein. A pair of support bars 100 are secured to the outlet members 96 at either end of the rectangular hopper portion 80 and are also secured to the rectangular portion 80 as by the bolts 102 and spacing collars 104. It may be noted that the support bars 100 on the right-hand side as viewed in Fig. 5 are provided with extension portions 105 for a purpose apparent hereinafter.

A plurality, in this instance two, pairs of feeding nozzles 106 of generally rectangular form are adapted for slidable movement relative to the nozzle portions 98 respectively to form a telescopic connection therewith. Each pair of feed nozzles 106 is connected at either end of the rectangular hopper portion 80 by cross-bars 108 which are mounted on four rack members 110 respectively and are each cooperable with a pinion 112 for imparting movement thereto. Each pair of pinions 112 is secured on the projecting ends of a rod 114 extending across the rectangular portion 80. The support bars 100 also serve to carry a guide element 116 for each rack 110 opposite the pinion 112. An additional pair of guide elements 118 are provided on the support bars 100 for the rack 110 in suitably spaced relation.

The extension 105 of the support bars 100 carries a bracket 120 upon which is mounted a fluid motor 122 having suitable connection with one of the racks 110 for reciprocating the same and rotating the pinion 112. There are two motors 122 at one end of the hopper portion 80 for operating the two racks 110 at that end and transmitting movement to the pinions 112 at the opposite end through the rods 114. Alternatively, the telescopic movement of the feed nozzles 106 can be imparted by manual means instead of by the motors 122. Thus, a handle (not shown) can be secured to the projecting end of the rod 114 for rotating the pinion 112 and thus moving the associated rack 110. It will be apparent that the movement of the feed nozzles 106 relative to the portions 98 can be adjusted to any desired amount and the purpose of such adjustment will be apparent hereinafter.

Receiving and pressure chambers

Positioned beneath the carriers 10 at the unloading stations on each carrier is a receiving chamber 140 having tapered sides to direct unloaded material to the center portion thereof. The receiving chamber 140 may be made of sheet material and embedded in the foundation 16 with its upper edge level with the floor line 12. A portion of the foundation 16 both beneath and slightly off-set from the receiving chamber 140 may be recessed as at 142 for the reception of a pressure chamber device 144. A flanged head 146 on the pressure chamber device 144 is securely attached to the receiving chamber 140 at the central portion which is suitably apertured to admit unloaded refractory material to the pressure chamber 144.

The pressure chamber device 144 comprises a tubular body member 148 depending from the flanged head 146 and terminating in a conical outlet 150. A discharge pipe 152 is connected to the conical end 150 and extends through the recess 142 to emerge from the foundation 16 at a point remote from the carriers 10. The pipe 152 then extends upwardly from the floor line 12 and is reversely curved to connect with a centrifugal separator element 154 which may be mounted on the hopper 78 for returning the refractory material thereto. A suitable exhaust system 156 may be employed in conjunction with the separator 154 to remove any dust or foreign matter which may be included in the refractory material being returned through the pipe 152 to the hopper 78.

The pressure chamber 144 contains a check valve element 158 which is mounted for swinging movement to open and close the outlet 147 of the receiving chamber 140. Thus, a pivoted arm 160 is shown in Fig. 7 as mounted on a rod 162 supported in the wall of the flange 146 and having an operating lever 164 mounted thereon. The opposite end of the lever 164 is engaged by a plunger 166 of a pressure motor 168 which is mounted on the flange 146. Reciprocation of the plunger 166 by the motor 168 will impart the desired swinging movement to the valve member 158 through the connections described. The pressure fluid connections for operating the motor 168 will be described hereinafter.

The pressure chamber 144 has a plurality of fluid connections two of which are indicated at 170 in Fig. 3. By application of pressure to the chamber 144 when the valve member 158 is in closed position the refractory material is transported through the pipe 152 and the separator 154 to the hopper 78 and to the point of delivery. The fluid connections for the pressure chamber 144 will be described in detail hereinafter.

During operation of the machine a suitable cover plate 172 is placed across the recess 142 to provide a firm surface for the operating personnel to stand upon.

Operation

In the general operation of the machine, it may be assumed that all of the casting boxes 58 are empty and ready for the positioning of molds in opposite boxes 58

of the two carriers 10. This operation is conducted in the boxes 58 which are positioned immediately in front of the refractory material loading station. This is the unloading station for both the refractory material and the finished castings. In practice, the refractory material is dumped in a matter of seconds, the castings removed and new molds inserted while at the same time the preceding box 58 is being loaded with refractory material at the loading station. After the loading operation is completed, the carrier 10 is indexed and the dumping of the refractory material and castings and the insertion of new molds is repeated. After several boxes 58 have been loaded in this manner, the pouring operation is commenced with the loaded boxes beyond the hopper 78 which are in positions 1, 2 and 3, for example. By the time these poured molds reach the dumping station, the casting material will be sufficiently cooled for the unloading operation. The cycle may continue indefinitely in accordance with foundry requirements.

With this brief description of the general operation presented, a detailed description of each operation will now be given. Since the operations are duplicated on each carrier the description of one will suffice for both.

Loading operation

With the two halves of the mold positioned centrally in a casting box 58 positioned at the refractory material loading station, the nozzle portions 98 of the outlet members 96 will be positioned on either side of the mold and immediately over the casting box 58. The feed nozzles 106 may then be lowered a predetermined amount into the casting box 58 by manual operation of the pinion 112 and rack 110 or by power operation of the motor 122 through manipulation of a multiway valve 174. This adjustment is determined by the operator according to the height of the molds in the casting box, it being apparent that the refractory material should not cover the pouring basins provided in the molds for the casting material. The motor 122 receives pressure fluid from a main line 176, shown in Fig. 6, and having a water separator 178 and filter 180 incorporated therein.

The gates 84 are now moved to the open position by operation of the toggle mechanism 86 by the plunger 88 of the motor 90. The connections for this purpose are shown in Fig. 6 as comprising a multiway valve 184 which can be manipulated to control flow of pressure fluid from the fluid pressure line 176 to the motor 90. As will be observed, two such motors 90 and connections are shown in Fig. 6 for operating the gates 84.

With the gates 84 in open position, refractory material will flow from the hopper 78 through the nozzle portions 98 and the lowered feeding nozzles 106 into the casting boxes 58. Such flow automatically ceases when the loaded material is approximately level with the outlet ends of the feeding nozzles 106 within the casting boxes 58. The multiway valve 184 is then manually operated to reverse the stroke of the plunger 88 of the fluid motor 90 and close the gates 84 controlled thereby.

An important feature of this invention now comes into operation. It will be apparent that while the flow of material from the hopper 78 is cut-off by operation of the gates 84, that both the feed nozzles 106 and the discharge ends 98 of the adapters 96 are at such times filled with refractory material. The feed nozzles 106 are now retracted either manually by operation of the pinion 112 and rack 110 or by the motor 122 due to operation of the multiway valve 174. The nozzles 106 will thus assume their initial positions relative to the discharge ends 98. During this retracting operation, the refractory material which was contained in these members will flow therefrom into the casting boxes 58 bringing the material to the desired level which has been predetermined by the depth to which the feeding nozzles 106 were lowered into the casting boxes 58.

After the casting boxes 58 have been filled in this

manner, fluid pressure is admitted through the connections 74 to the space between the liners 72 and the wall of the casting boxes 58. Such fluid pressure is admitted on each side of the mold within the casting box 78 and thereby compresses such mold sufficiently to withstand the static pressure of the casting metal. As shown in Fig. 6, a separate conduit 224 is provided for supplying each of the connections 74 and the conduits 224 may be controlled individually by shut-off valves 226. The conduits 224 extend from the casting boxes to a rotatable pressure joint 228 which surmounts the hub member 18 and is provided with a supply conduit 229 extending through the support 14 having a reducing valve 230 and indicator 232 interposed therein. By operation of the reducing valve 230, the fluid pressure in the casting boxes 58 may be set to approximate or exceed the static pressure of the casting material in the mold as will be understood.

Pouring operation

The casting boxes 58 which have now been loaded may be indexed through the unloading station to one of the pouring positions as previously described.

Thus, by manipulation of a multiway valve 233, fluid pressure is admitted to the motor 42 so that the plunger 44 operates the swivel connection 46 to rotate the fluid motor 32 about its pivot 34 against the bias of the spring 40. Hence, the notched portion 38 is moved out of operative engagement with the related stud 26. It should be observed that the fluid pressure from multiway valve 233 does not act on fluid motor 32 until such pressure has become sufficiently high to overcome a suitable sequence valve 235. The valve 235 is provided for the purpose of permitting motor 42 to act before pressure is admitted to the fluid motor 32 for freeing the notched portion 38 from the stud 26 as described.

The multiway valve 233 is preferably of the neutral position type so that all its ports are open. Thus, when the neutral position is reached, the fluid pressure in motor 42 drops to zero and plunger 44 is returned to its initial or starting position under the bias of the spring 40. Since the fluid motor 32 is also under the bias of the spring 40, a swinging motion in reverse occurs about its pivot 34 causing the notched portion 38 to engage the next stud 26 in line. Now, by manually reversing the multiway valve 233, fluid pressure is admitted to the motor 32 for advancing the plunger 36 and notched portion 38 thereby indexing the carrier 10 as soon as the engagement occurs between the stud 26 and notched portion 38.

A suitable conveyor (not shown) may be employed for handling the casting material from the point of melting to the pouring position. After the pouring operation, the carriers 10 are indexed to the unloading station as previously described which is immediately in front of the loading station. Prior to unloading, the fluid pressure within the casting boxes is exhausted by operation of the shut-off valve 226 to free the refractory material for the unloading operation.

Unloading operation

The unloading operation is conducted by opening the bottom wall 62 of the casting boxes and permitting the refractory material to drop by gravity into the receiving chamber 140. Thus, in the unloading position the catch 64 for operating the bottom walls 62 is in position to be engaged by the pressure motor 66 which is under the control of a multiway valve 234 connected in the pressure system of the line 176. Suitable manual manipulation of the valve 234 will thus operate the bottom wall 62 to empty the casting box 58 at the unloading station.

The refractory material drops into the receiving chamber 140 and the check valve 158 is operated to admit this material to the pressure chamber 144. Such operation need only be conducted when the receiving chamber 140 is sufficiently filled with refractory material. The fluid

motor 168 controlling the check valve 158 is connected, as shown in Fig. 6, to the fluid pressure line 176 through a multiway-solenoid operated valve 185. The connections to opposite ends of the fluid motor 168 from the valve 185 embody a suitable type of sequence valve 218 in the connection for opening the check valve 158 and a reverse action pressure switch 222 in the connection for closing the valve 158. The pressure switch 222 is adapted to close at approximately 75 p. s. i. fluid pressure and to open at approximately 40 p. s. i. fluid pressure.

As previously stated, the fluid connections for the pressure chamber 144 include connections 170 leading to the chamber 144. These connections 170 are supplied jointly from the conduit 229 by an auxiliary conduit 231 which includes a solenoid operated shut-off valve 252 controlling the flow of pressure fluid therethrough. The pressure chamber also has a suitable pressure switch 190 connected thereto and adapted to close at approximately 20 p. s. i. fluid pressure and open at approximately 40 p. s. i. fluid pressure. This switch 190 is hence of the regular action type as distinguished from the reverse action of the switch 222.

Referring to the wiring diagram Fig. 8, the circuit for the solenoid valve 185 may be traced from line wire L1, wires 186, 188, pressure switch 190, wire 192, signal lamp 194, wire 196, primary of transformer 198, and wire 200 to line wire L2. The secondary of the transformer 198, now energized, has one terminal connected by wire 202 to ground and the opposite terminal thereof connected by wire 204 to one terminal of a micro-switch 206. The switch 206 is of the double-throw type having an opposite terminal connected by wire 208 to one terminal of the solenoid valve 185, the opposite terminal of which is connected by wire 210 to another terminal of the switch 206. The solenoid valve 185 has a pair of coils 212 and 214 for advance and retract operations respectively and is provided with a center tap 216 to ground.

Since the switch 190 is deemed to be closed and the micro-switch 206 is in position for closing the circuit to the advance solenoid 212, then fluid pressure is admitted to the end of the pressure motor 168 controlled by the sequence valve 218 for opening the check valve 158 controlling the flow of refractory material to the chamber 144. When the pressure chamber 144 is filled with refractory material the check valve 158 is operated to closed position by manual operation of a push button 220 operably associated with the micro-switch 206. Such operation serves to operate the micro-switch 206 to open the circuit of the advance solenoid coil 212 previously traced and to close a circuit for the retract solenoid coil 214 by way of wire 210. Pressure fluid is now admitted by operation of the solenoid valve 185 to the opposite end of the fluid motor 168 for closing the check valve 158. The pressure chamber 144 is now filled with refractory material and is pressure tight.

The chamber 144 is emptied by admitting fluid under pressure through the connections 170 as described. It is apparent that as the fluid pressure to the motor 168 for closing the check valve 158 reaches 75 p. s. i. or as the system pressure in supply line 176 may be 75 p. s. i. or more, then pressure switch 222 becomes closed due to its reverse action and establishes a circuit for the solenoid valve 252 as follows: Line wire L1, wire 186, pressure switch 222, wire 250, coil 251 of solenoid valve 252, wire 254 and wire 200 to line wire L2. The opening of the solenoid valve 252 admits fluid under pressure from the conduit 229 to the pressure chamber 144 and the refractory material is transported back to the hopper 78 as described. The pressure in the chamber 144 reaches that for which the pressure switch 190 is set (40 p. s. i.) in a matter of $\frac{1}{10}$ second and this switch 190 will consequently be moved to open position. Such operation will open the circuit of the primary of transformer 198 and deenergize the retract solenoid coil 214 while extinguishing the signal light 194. The operator may now release

the push button 220 and cause the switch 206 to reestablish the secondary circuit through coil 212 of the solenoid valve 185.

Upon the chamber 144 becoming emptied of refractory material, the fluid pressure therein is substantially instantly reduced to zero and the pressure switch 190 thereby closes. The circuit through the primary of transformer 198 is reestablished and since the secondary circuit was previously closed the coil 212 becomes energized. The position of the solenoid valve 185 is thus reversed. However, the fluid pressure affecting the pressure switch 222 soon drops to zero as this pressure overrides the sequence valve 218 and acts to reverse the fluid motor 168. It should be observed that the sequence valve 218 serves to delay opening of the check valve 158 to permit the pressure switch 222 to shut off fluid pressure to the pressure chamber 144. The check valve 158 then opens, the signal lamp is illuminated, and the system is in condition for another cycle.

It will be apparent that many changes may be made in details of construction and arrangement of parts and that certain phases of the cycle may be rearranged or omitted without departure from the scope of the invention as defined in the appended claims.

I claim:

1. In a casting machine, the combination of a carrier having support means movable through a predetermined path, separate loading and unloading stations adjacent said carrier, a plurality of casting boxes, means for mounting said boxes on said support means for movement therewith along said path and through said stations, means in each of said boxes for supporting a completed mold therein and positioning the same to define a space between the mold and at least one side of said box, a container for granular refractory material having discharge means at said loading station for loading said material into said space to support the completed mold, and means operable at said unloading station for emptying said boxes of said material.

2. In a casting machine as claimed in claim 1 the combination of means operable for returning said material to said container.

3. In a casting machine, the combination of a carrier, a loading station adjacent said carrier, a plurality of casting boxes mounted on said carrier for movement in sequence through said station, means in each of said boxes for supporting a completed mold therein and positioning the same to define a space between the mold and at least one side of said box, a container for flowable granular refractory material having a discharge outlet at said loading station, feeding means communicating with said outlet and being movable into said boxes to a predetermined depth adjacent the molds supported therein, means for controlling passage of said material from said outlet into said space for loading therein an amount set by said feeding means, and means for withdrawing said feeding means upon completion of said loading operation.

4. In a casting machine as claimed in claim 3 the combination of a separate unloading station adjacent said carrier, means operable at said unloading station for emptying said boxes of said material, and means operable for returning said material to said container.

5. In a casting machine, the combination of a rotary carrier having radial arms thereon, separate loading and unloading stations adjacent said carrier, a plurality of casting boxes mounted on said arms in end-to-end relation forming a fixed rim portion of a wheel, said boxes being adapted to be retained on said carrier for movement in sequence through said stations, means in each of said boxes for supporting a completed mold therein and positioning the same to define a space between the mold and at least one side of said box, a container for granular refractory material having discharge means registering with said boxes at said loading station for loading said material into said spaces to support the completed molds,

means for controlling passage of said material from said container to said space, and means operable at said unloading station for emptying said boxes of said material.

6. In a casting machine, the combination of a rotary carrier having radial arms thereon, separate loading and unloading stations adjacent said carrier, a plurality of casting boxes mounted on said arms in end-to-end relation forming a fixed rim portion of a wheel, said boxes being adapted to be retained on said carrier for movement in sequence through said stations, means in each of said boxes for supporting a completed mold therein and positioning the same to define a space between the mold and at least one side of said box, a container for granular refractory material having discharge means movable relatively to said boxes at said loading station for loading said material into said spaces to support the completed molds, closure means movable between open and closed positions for controlling passage of said material from said discharge means to said spaces, means carried by said container for moving said closure means between said positions, means for compressing said material in said boxes around the molds, and means operable at said unloading station for emptying said boxes of said material.

7. In a casting machine, the combination of a rotary carrier having radial arms thereon, separate loading and unloading stations adjacent said carrier, a plurality of casting boxes mounted on said arms in end-to-end relation forming the rim portion of a wheel, said boxes being adapted to be retained on said carrier for movement in sequence through said stations, means in each of said boxes for supporting a completed mold therein and positioning the same to define a space between the mold and at least one side of said box, a container for granular refractory material having a discharge outlet at said loading station, feeding means communicating with said outlet and being movable into said spaces respectively to a predetermined depth, closure means movable between open and closed positions for controlling passage of said material from said discharge outlet to said spaces for loading therein an amount set by said feeding means, means carried by said container for moving said closure means between said positions, means for withdrawing said feeding means upon completion of said loading operation, means for compressing said material in said boxes around molds supported therein, and means operable at said unloading station for emptying said boxes of said material.

8. In a casting machine as claimed in claim 7 the combination of means operable for returning said material to said container.

9. In a casting machine, the combination of a carrier, a loading station adjacent said carrier, a plurality of casting boxes mounted on said carrier for movement in sequence through said station, means in each of said boxes for supporting a completed mold therein and positioning the same to define a space between the mold and at least one side of said box, power means movable into operative engagement with said carrier for indexing said boxes through said loading station, a container for flowable granular refractory material having a discharge outlet at said loading station, feeding means communicating with said outlet and being movable into said spaces in said boxes adjacent the molds supported therein, manually operable means for adjusting said feeding means to a predetermined depth in said boxes, closure means movable between open and closed positions for controlling passage of said material from said outlet into said spaces for loading therein an amount set by said feeding means, said manually operable means being operable for withdrawing said feeding means upon completion of said loading operation.

10. In a casting machine, the combination of a conveyor having support means movable through a predetermined path, separate loading and unloading stations adjacent said conveyor, a plurality of casting boxes, means

11

in each of said boxes for supporting a completed mold therein and positioning the same to define a space between the mold and at least one side of said box, means for mounting said boxes on said support means for movement therewith along said path and through said stations, a container for granular refractory material having discharge means at said loading station for loading said material into said spaces to support the completed molds in said boxes, means responsive to the level of said material in said boxes for terminating flow of said material through said discharge means when said material in said boxes reaches a predetermined level, and means operable at said unloading station for emptying said boxes of said material.

11. In a casting machine, the combination of a casting box, means in said box for supporting a completed mold therein and positioning the same to define a space between the mold and at least one side of said box, a container for flowable granular refractory material, means including a hollow element defining a passage communicating with said space and the interior of said container, said element being movable into said space to a predetermined depth adjacent a mold supported in said box, and gate means for controlling the flow of said material in said passage.

12. In a casting machine, the combination of an open ended casting box, means in said box for supporting a completed mold along a central vertical plane thereof and spaced from the sides thereof, a container for flowable granular refractory material, means including a pair of spaced hollow elements defining a pair of passages communicating with the interiors of said box and said container, said elements being movable into said box to a predetermined depth and adapted to straddle a mold supported therein, and gate means for controlling the flow of said material in said passages.

12

13. In a foundry apparatus for casting, the combination of a conveyer movable through a predetermined path, separate loading and unloading stations, a plurality of open-ended containers on said conveyer and arranged to be moved thereby along said path and through said stations, gate means operable for closing the bottom ends of said containers, means associated with each of said containers for supporting a completely formed mold therein and positioning the same to define a space between the mold and at least one side of said container, means at said loading station for loading granular refractory material into said space in each of said containers to support the mold disposed therein, and means for operating said gate means to open the bottom ends of said containers at said unloading station and discharge said material therefrom.
